EDWARD O. TINSLEY, OF NEW YORK, N. Y., ASSIGNOR TO ROBERT GAIR COMPANY,
OF NEW YORK, N. Y., A CORPORATION OF NEW YORK

SHIPPING AND DISPLAY CARTON

Application filed April 25, 1928. Serial No. 272,724.

This invention relates to cartons and cardboard blanks therefor and more particularly to cartons for carrying fragile articles and protecting them against breakage, though it is noted that the invention is not limited to 5 cardboard cartons nor in some respects even to cartons for fragile articles.

One object of the invention is to provide a container of this kind having therein a partition provided with nests or seats for holding 10 articles out of contact with the container.

Another object of the invention is to provide a device of this kind in which the articles may be easily displayed while nested.

Another object of the invention is to provide 15 an improved closing means for cartons of this kind or for other types of containers.

Another object is to provide an improved one-piece blank for making the carton.

Other objects of the invention are to improve 20 generally the simplicity and efficiency of such cartons and to provide a carton of this kind which is durable, and sightly in use, easy to set up, and economical to manufacture.

Still other objects of the invention will appear 25 as the description proceeds; and while herein details of the invention are described and claimed, the invention is not limited to these, since many and various changes may be 30 made without departing from the scope of the invention as claimed in the broader claims.

The inventive features for the accomplishment 35 of these and other objects are shown herein in connection with an improved carton which, briefly stated, includes a bottom to which are foldably joined a front wall and a rear wall, end walls joining the rear wall. The front wall is of less height than the rear wall, and a partition extending from and 40 joining the upper edge of the front wall to the rear wall providing upper and lower chambers to the carton is provided with nests for receiving and holding electric bulbs or other articles out of contact with other parts of the 45 carton.

A cover for said outer chamber comprises a lid top foldably joined to the upper part of the rear wall and provided at its free edge with a closing piece to close the front of the 50 outer chamber.

In the accompanying drawing showing, by way of example, one of many possible embodiments of the invention,

Fig. 1 is a perspective view of the container 55 closed;

Fig. 2 is a perspective view of the container in open condition;

Fig. 3 is a transverse vertical sectional view, partly in elevation, showing the article nested in the carton, the section being taken substantially on the line 3—3 of Fig. 1, looking in the direction of the arrows of said line;

Fig. 4 is a fragmental longitudinal vertical sectional view, partly in elevation, showing an inner face view of the closing piece, the section being taken substantially on the line 4—4 of Fig. 3, looking in the direction of the arrows of said line; and

Fig. 5 is a face view of the blank.

My improved carton is formed of a one-piece blank 5 (Fig. 5) cut and folded to form a bottom 6 (Figs. 3 and 4) having upturned end flaps 7.

A rear wall 8 is foldably joined to the rear edge of the bottom and is provided with end 75 walls 9 forwardly disposed against the flaps 7, rounded at the upper front corners 10 and foldably joined to the ends of the rear wall and provided near and above their lower rear corners with rearwardly upwardly inclined 80 slits 11.

A front wall 15 about half the height of the rear wall is foldably joined to the front edge of the bottom and provided with end flaps 16 foldably joining the ends of the front wall 85 and disposed against the lower part of the outer face of said end walls 9 and provided at the lower rear corners with downwardly pointed tabs 17 disposed in said slits 11 to hold the walls to place.

A platform or partition 20 joins and rearwardly extends from the upper edge of the front wall 15, dividing the carton into an upper or outer chamber above the platform and a lower or inner chamber beneath the platform. The platform is provided with downwardly disposed end and rear flanges 21, 22 disposed against said walls and resting against the bottom to support the platform, the lower edge of the rear flange being pro- 100

vided with a forward flap 23 disposed flat on the bottom and engaging the front wall and the flanges 21, 22 to hold the flanges in supporting position.

5 Said platform or partition 20 is provided with a longitudinal series of nests 24 formed by a plurality of radial slits 25, the slits of each nest extending from a common center and terminating at a common circumference, thereby to form separate friction fingers 26 joining the body of the platform at said circumference and adapted to be forced downwardly (Fig. 3) into the inner chamber, as by the insertion of the neck of an electric light bulb 27 or other suitable article, thereby to cause the fingers to frictionally engage the articles and hold the articles in the nests, thereby to hold the articles against contact with any outer or other structure of the carton except said fingers, thereby to protect the articles against breakage.

A cover for said outer chamber comprises a lid top 29 hingedly joined to the upper edge of the rear wall 8 and a closing piece 30 joining the free edge of the top. At each end of the top are end pieces 31 disposable on the outside of the end walls 9 and each provided at its edge 32, which is the front edge when the cover is closed, with an elongated flap 33 each disposed flat against and covering the inner face of the closing piece 30 (Fig. 4) for more than a quarter of its length. Each flap 33 is provided with rectangular cut-out 34 about midway of the edge of the flap which is lowest when the flap is closed.

35 A retaining piece 35 foldably joining the entire free edge of the closing piece is disposed flat against the exposed faces of said flaps 33 and provided near the ends with wide 40 tongues 36 passing through the inner end of said cut-outs and disposed between the flaps and the closing piece, thereby to retain the retaining piece and flaps folded adjacent to the inner face of the closing piece 30.

45 The middle part of the retaining piece 35 is wider than the end parts and cut as at 39 to form a recess 39 and a tongue 40 (Fig. 2) joined to the free edge of the closing piece 30 and provided at its free end with a pair of 50 appositely pointed locking tabs 41 disposable in said recess 39 when the tabs are not in use, or disposable at the front of the front wall for locking.

The front wall 15 is provided with a pair of spaced locking slits 42 adapted to receive the tabs 41 for holding the cover closed over the upper chamber. The score lines 43 facilitate insertion of the tabs.

Fig. 5 shows the blank 5 provided with score lines 32, 43, 44 on its inner face separating the various structures above described, and from which the container may be easily constructed by persons skilled or not skilled in the art of box making.

65 The exteriorly exposed faces of parts 6, 8,

9, 15, 20, 29, 30, 31, 33, 35 and 40 all on the same face of the blank making it possible to ornament, by printing one face of the blank only, all of the exterior of the carton when closed and most of the exposed parts when open. 70

While in this specification and claims I speak of the bottom, top, ends front and rear of the container and mention that parts are foldably joined, it is understood that I use these words for designation and that they are to be construed broadly enough to cover the container in other relative dimensions or positions than as shown, and where parts are connected by other than score lines, and in general the terms are to be given broad interpretation.

I claim as my invention:

1. A carton comprising a bottom; a rear wall joining the rear of the bottom; end walls, the same height as the rear wall, joined to the rear wall and having a horizontal top edge and a vertical front edge; a front wall less than the height of the rear wall joined to the front of the bottom; a platform extending from the upper edge of the front wall to the rear wall; and a cover comprising a lid top joined to the top of the rear wall, provided at its free edge with a closing piece resting on the platform and having end pieces holding the lid and top at right angles to each other; the upper and front margins of the upper part of the end walls co-operating with said lid top, end pieces and retaining piece to strengthen the front upper corners of the carton. 100

2. A carton comprising a bottom; a rear wall joining the rear of the bottom; end walls joined to the rear wall and having horizontal top edges and vertical front edges; a front wall less tall than the rear wall joined to the front of the bottom; a platform extending from the upper edge of the front wall to the rear wall; a lid top joined to the upper edge of the rear wall and disposable to rest on said upper edges of the end walls and provided with end pieces disposable against the outer face of the end walls; a closing piece joining the free edge of the lid top having its lower edge resting on the top edge of the platform. 105 110

edge resting on the top face of the platform; 115
each of said end pieces being provided at its
front edge, with an elongated flap disposed
flat against and covering the face of the
closing piece each provided with cut-out in
the lower edge of the flap; and a retaining
piece foldably joining the free edge of the
closing piece and disposed flat against said
elongated flaps and provided with tongues
passing through the cut-outs and disposed
between the flaps and the closing piece, thereby
to secure the closing and end pieces and
lid top strongly together; the upper and
front margins of the upper part of the end
walls co-operating with said elongated flaps 120
125
130

and retaining piece to strengthen the front upper corners of the carton when closed.

3. A carton comprising a bottom; a rear wall joining the rear of the bottom; end walls joined to the rear wall; a front wall less than the height of the rear wall joined to the front of the bottom; a platform rearwardly extending from the upper edge of the front wall, and provided with downwardly disposed end and rear flanges disposed against said walls and resting against the bottom to support the platform; the lower edge of the rear flange being provided with a forward flap disposed flat on the bottom and engaging the front and end walls to hold the rear flange and end flanges in position against the end and rear walls.

4. A carton comprising a rectangular bottom having upturned end flaps of the same width as the bottom; a rear wall taller than the end flaps and joined to the rear of the bottom and provided with forwardly disposed end walls and engaging the outer face of the end flaps and foldably joined to the ends of the rear wall; a front wall about the same height as the end flaps and joined to the front of the bottom and provided with end flaps secured against the outer face of said end walls; a platform rearwardly extending from the upper edge of the front wall, and provided with downwardly disposed end and rear flanges disposed against said rear wall and the end flaps of the bottom respectively and resting against the bottom; the lower edge of the rear flange being provided with a forward flap disposed flat on the bottom and engaging the front wall and end flanges to hold the rear and end flanges in position and the end flaps of the rear wall against the end and rear walls.

5. A carton comprising a bottom; a rear wall joining the rear of the bottom; end walls joined to the rear wall; a front wall less than the height of the rear wall joined to the front of the bottom; a platform extending from the upper edge of the front wall to the rear wall; a cover disposed entirely above the level of the platform, comprising a lid top joined to the top of the rear wall and provided at its free edge with a closing piece resting on the platform; and means for fastening the middle of the closing piece to the front wall.

6. A carton comprising a bottom; a rear wall joining the rear of the bottom; end walls joined to the rear wall; a front wall less than the height of the rear wall joined to the front of the bottom; a platform provided with nests and extending from the upper edge of the front wall to the rear wall; a lid top hingedly joined to the upper edge of the rear wall and provided with end pieces disposable against the outer face of the end walls; a closing piece joining the free edge of the lid top having its lower edge adapted to rest on the top face of the platform; each of said end

pieces being provided at its front edge, with an elongated flap disposed flat against and covering the face of the closing piece each provided with cut-out in the lower edge of the flap; and a retaining piece foldably joining the free edge of the closing piece and disposed flat against the exposed faces of said elongated flaps and provided with tongues passing through the cut-outs and disposed between the flaps and the closing piece; 70 said flaps and retaining piece co-operating to strengthen the front edge of the closing piece to form a strong bridge portion engaging the front edge of the end walls, to protect articles in the nests.

7. A carton comprising a bottom; a rear wall joining the rear of the bottom; end walls joined to the rear wall; a front wall less than the height of the rear wall joined to the front of the bottom; a platform extending from the upper edge of the front wall to the rear wall; a cover comprising a lid top joined to the top of the rear wall and provided at its free edge with a closing piece resting on the platform; end pieces joining the ends of the lid top and closing piece and holding said top and closing piece at right angles to each other when the cover is opened or closed; and a fastening means for the cover carried by the middle of the lower part of the closing piece. 85

8. A carton comprising a bottom; a rear wall joining the rear of the bottom; end walls joined to the rear wall; a front wall less than the height of the rear wall joined to the front of the bottom; a platform extending from the upper edge of the front wall to the rear wall; and a cover comprising a lid top joined to the top of the rear wall and provided at its free edge with a closing piece resting on the platform, the free edge portion of the closing piece being folded back upon itself to form 100

a retaining piece secured against the inner face of the closing piece; the middle part of the retaining piece being cut to form a recess and a tongue therein joining the free edge of the closing piece and provided at its free end with a pair of oppositely pointed locking tabs disposable in said recess against the closing piece to be stopped thereby, or disposable against the front wall; the front wall being provided with a pair of spaced locking slits adapted to receive the tabs; the retaining piece being secured flat against the closing piece, whereby said pieces cooperate to form 110 a recess in which the tongue will be positioned by the closing piece when the tongue is pressed into the recess.

9. A carton comprising a bottom; a rear wall joining the rear of the bottom; end walls joined to the rear wall; a front wall less than the height of the rear wall joined to the front of the bottom; a platform extending from the upper edge of the front wall to the rear wall; and a cover comprising a lid top joined to the top of the rear wall and provided at 125

130

its free edge with a closing piece extending to the front edge of the platform; the middle part of the closing piece being cut to form a tongue joining the free edge of the closing piece and provided at its free end with a pair of oppositely pointed locking tabs disposable against the front wall; the front wall being provided with a pair of spaced locking slits adapted to receive the tabs; said tongue being provided with a pair of score lines extending from the inner end of the top edge of the tabs, and meeting at the middle of the lower edge of the tongue, to facilitate insertion of the tabs.

15 Signed at New York, in the county of New York and State of New York, this 24th day of April, A. D. 1928.

EDWARD O. TINSLEY.
